UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed July 2, 1921. Serial No. 482,056.

To all whom it may concern:

Be it known that I, BURNHAM C. STICKNEY, a citizen of the United States, residing at Elizabeth, in the county of Union and 5 State of New Jersey, have invented certain new and useful Improvements in Typewriting Machines, of which the following is a specification.

This invention relates to sound-deadening hoods or casings for typewriting machines, and is of the same general type 10 shown in my application, Serial No. 429,617, filed December 10, 1920, and in the application of John Waldheim, Serial No. 466,820, 15 filed May 4, 1921.

The casing comprises a body part, and a cover hinged at the rear to the body part, said body part having a large front opening through which the machine may be 20 inserted into the casing, and a removable front cover plate for closing the opening after the machine has been inserted.

A longitudinal slot is provided at the front between the cover and the body part, 25 through which various operating levers on the traveling typewriter carriage, such as the line-space lever, the carriage-return lever, and the carriage-release lever, may project, so that the ordinary operation of 30 the machine may be carried on without raising the cover of the casing. To close all of the slot not occupied by these operating levers, there are provided co-operating 35 cushions of sound-deadening material attached to the body part and cover, respectively. When the carriage-release lever is operated, the lower cushion will ordinarily be depressed, and, to prevent excessive crushing of said cushion, that portion of 40 the lower cushion over which the carriage-release lever operates is floatingly mounted on the body part, so that it is depressible bodily by the lever.

Another feature of this invention is the 45 provision of means for transmitting the sound of the line-end bell-signal to the outside of the casing and forwardly toward the operator. Said means comprises a horn mounted in the side of the casing, one end 50 of the horn opening to the outside of the casing, its other end projecting inwardly into the body of the typewriting machine

and terminating adjacent the bell, said horn being collapsible, so that the portion thereof which projects into the machine may be withdrawn when it is desired to remove the machine from the casing. The horn opens at its outer end to the outside of the casing at one side thereof, and, to transmit the sound forwardly, there is mounted on the 60 side wall of the casing a deflector having one end thereof in communication with the outer end of the horn, and the other end thereof extending forwardly toward the front of the casing. The horn is mounted 65 so that the bell closes its inner end, thus preventing sounds other than those due to the bell from escaping to the outside of the casing.

It is another feature of this invention to 70 provide means whereby it shall be possible to operate the ribbon-winding mechanism without removing the casing. For this purpose, there is provided an opening in the side wall of the casing adjacent the ribbon-winding mechanism, to allow access to said mechanism. A pivotally mounted door may be provided, which, when opened, allows 75 access to the ribbon-winding mechanism, but which is normally closed to prevent escape 80 of sound through the side of the casing.

Other features and advantages will hereinafter appear.

In the accompanying drawings,

Figure 1 is a front view, partly sectioned, 85 of an Underwood standard typewriting machine having the sound-deadening casing applied thereto.

Figure 2 is a side view, partly sectioned, 90 of the device shown in Figure 1.

Figure 3 is a plan view of the device shown in Figure 1, the cover of the casing having been removed.

Figure 4 is a detail perspective view, 95 showing the method of mounting the portion of the lower cushion which co-operates with the carriage-release lever.

The Underwood standard typewriting machine comprises a main frame 10, supported upon a base 11 by means of supporting feet 12 fixed thereto, and is provided with a forward extension 13 in which are positioned banks of keys 14. Said keys operate type-bars (not shown) to cause types,

carried by said type-bars, to print against a platen 15 journaled in the end walls 16 of a platen-frame 17, forming part of the usual typewriter carriage 18 which is 5 mounted for letter-feeding movement upon a front rail (not shown) and a rear rail 19 on the main typewriter frame. The carriage is provided with the usual forwardly and downwardly extending operating levers, 10 such as the carriage-release lever 21, the carriage-return finger-piece 22 and the line-space handle 23. The typewriting machine is provided with a bell 25, positioned preferably at one side of the machine, here 15 shown as the left side, for signaling the approach of the end of a line; and with the usual ribbon-winding mechanism, shown partially and indicated generally at 27, and comprising a handle 28, said ribbon-winding 20 mechanism being positioned preferably at the right side of the machine.

For deadening sounds arising in the typing operation, there is provided a sound-deadening casing or hood, comprising a body part 30 and a cover 31, hingedly connected to said body part at 32. The body part 30 comprises a rear wall 35, side walls 36 and a front wall, in the form of two sections, 37, said sections being spaced apart 30 to provide a large front opening through which the machine may be inserted into the casing, said body part being provided with lateral extensions 39 over which the carriage operates to the right and left. The machine 35 is positioned within the body part by means of abutments 40, fixed to the rear wall 35 of the body part; the forward extension 13 projecting forwardly from the casing after the machine has been positioned therein. 40 For closing all of the front of the casing not actually occupied by the forward extension 13, there is provided a front plate 42, having hooks 43 fixed to the rear thereof, said hooks engaging in slots 44 in the front 45 portion 37, whereby the front plate may be mounted upon the body part of the casing. The front plate 42 may be removed by raising the plate so that hooks 43 may be withdrawn from slots 44. When the front plate 50 has been attached, the machine, with the exception of the forward extension, is enclosed at the rear, sides, and front. To enclose the casing at the top, there is provided the cover 31 comprising a rear wall 45, a top 55 wall or ceiling 46 forming a continuation of said rear wall 45, said top wall being provided with a transparent plate 47 to permit the interior of the casing to be viewed; and a front wall 50, terminating above the upper 60 edge of the front plate 42. The front wall 50 terminates above the front plate 42 a sufficient distance to form a slot, through which the operating levers 21, 22 and 23 project, and in which said levers operate. To 65 close all of the slot not actually occupied by

these operating levers, there is provided a cushion 52 of sound-deadening material, such as plush, felt or soft leather, in the form of a loop whose two-ply edges are clamped between bars 53, to form a unit 70 which is mounted upon the front wall 50, so that the loop 52 extends downwardly to close that portion of the slot between the front wall 50 and the operating levers. To close the portion of the slot between the 75 front plate 42 and the levers, there is provided a similar cushion 55, mounted on the front plate 42 and extending upwardly to contact with cushion 52, said cushion 55, being substantially half the length of cushion 52. To contact with the right half of cushion 52, there is provided a cushion 56, similar to cushions 52 and 55, cushion 56, however, not being rigidly mounted upon the front plate 42. The carriage-release 80 lever 21 operates downwardly and upwardly and would ordinarily crush cushion 56 in its downward movement to such an extent as to render it difficult for said cushion to regain its original position, and would 90 unduly wear out said cushion, due to the travel of the carriage-release-lever, while the latter is depressed. To avoid unduly crushing and wearing out cushion 56, the latter is yieldingly mounted to move bodily 95 downwardly when the release-lever is depressed. For this purpose, the cushion 56 is clamped between two clamping bars 57, carried by arms 58, pivotally mounted on stub-shafts 59 in the upper ends of brackets 100 60, fixed to the front plate 42. The rear clamping bar 57 may be provided with an upper extension 63, extending upwardly substantially to the release-lever 21 in its normal position, so that, when said release-lever 105 is depressed, it will contact with said extension 63 before the cushion 56 has been crushed to any considerable extent to force said cushion bodily downward. Due to this means, the cushion 56 will not be rapidly 110 worn out, or crushed to such an extent as to render it difficult for it to regain its original shape. The cushion 56 and extensions 63 are normally maintained in raised position 115 in contact with the under side of the levers by means of springs 64 fixed to said stub-shafts 59 and to said arms 58. When the front plate is removed from the casing, the upward movement of cushion 56 and extension 63 may be limited by means of a projection 66 (Figure 2) fixed to the upper 120 end of bracket 60. It will thus be seen that the lower slot-closing strip comprises the two sections 55 and 56 which, together, are 125 equivalent to the upper slot-closing strip which is the cushion 52; and that only that part of the lower cushion over which the release-lever travels is compressible by said release-lever.

The bell 25, which is mounted adjacent 130

one side and within the body of the machine, will not ordinarily transmit the line-end or line-lock signal to the outside of the casing, since the latter completely encloses the 5 noise-producing portion of the machine. To transmit the sound of the line-end bell-signal to the outside of the casing, so that the operator will hear the signal, there is provided a horn 70, comprising a tube 71, having its outer end passing through the 10 side wall of the casing which is adjacent said bell, and a second tube 72, slidably mounted within said tube 71, by means of headed studs 73, fixed to the tube 72 and 15 operating in slots 74 in the tube 71, said inner tube 72 being movable inwardly by means of a handle 75 fixed thereto until the inner end of said tube is near the bell 25. The handle preferably extends upwardly and operates in the space between the side of the machine and the side of the casing. The sound of the bell will thus pass through said horn to the outside of the casing, and, to render said signal still more 20 audible to the operator, there is attached to the outer end of the horn, upon the outside of the casing, a deflector 77, having its front end opening adjacent the front of the casing. The bell 25 lodges in and substantially 25 fills the inner end of tube 72, so that, while the bell-signal is transmitted to the outside, it is not possible for other noises arising in the operation of the machine to be transmitted through said horn. It will 30 be noted that the inner end of tube 72 extends inwardly into the body of the machine and would obstruct the machine when the latter was removed from the casing, unless said tube were previously withdrawn. 35 To withdraw the tube from the body of the machine, prior to removing the machine from the casing, the handle 75 is moved outwardly to cause tube 72 to telescope within the tube 71, the former sliding within the latter by means of the screws 73 operating 40 in slots 74 until the inner end of tube 72 is completely out of the path of the machine. The bell is preferably mounted upon the main frame of the machine by means of an arm 45 50 projecting upwardly from said frame, said bell being fixed to said arm preferably by a screw 81, the inner tube 72 being provided with a cutout portion 82 to clear said arm 80. The horn is thus collapsible, at will, 55 to permit the machine to be moved in or out of the casing.

The ribbon-winging mechanism 27 is positioned at one side and within the main body of the machine, so that it is contained 60 within the body portion of the casing below the extensions 39, which would ordinarily render access thereto difficult without removing the casing. To allow access to said mechanism without removing the casing, 65 there is provided in the side wall, adjacent

said mechanism, an opening 90, permitting access thereto. To prevent sounds arising in the typing operation from passing through said opening 90, there is provided a pivotally-mounted door 91, which may be 70 swung to open or closed position, preferably by a knob 92, said door being held in closed position by a spring-catch or detent 93, thus effectually closing the side of the casing during the operation of the machine. 75

To support the casing more firmly upon a base, the body part of the casing is provided with inturned flanges 95 at its lower end. The machine is held firmly in position within the casing by means of abutments 96 on the front plate 42 and the abutments 40 on the rear wall of the body part. The casing may be lined with any suitable sound-deadening material to more effectively 80 deaden the sound. 85

Variations may be resorted to within the scope of the invention, and portions of the improvements may be used without others.

Having thus described my invention, I claim:

1. The combination with a typewriting machine, comprising a carriage and a depressible release lever for said carriage, of a sound-deadening casing for said machine, said casing comprising a body part and a cover part, said body part and cover part forming a slot at the front through which said release lever projects, and means for closing all of said slot not occupied by the release lever, said means comprising oppositely disposed strips, one of said strips being supported on said cover part, the second strip being supported on said body part and comprising two sections, one of said sections being fixed to the body part, the other of said sections being movably supported on said body part, said release lever operating over the movably supported section to depress it bodily when the release lever is operated. 100

2. The combination with a typewriting machine, comprising a carriage and a depressible release lever for said carriage, of a sound-deadening casing for said machine, said casing have a slot at the front through which said release lever projects and along which it travels, and means for closing all of said slot not occupied by the release lever, said means comprising oppositely disposed cushioning strips, one of said strips being supported on said casing at the upper edge of said slot, the second strip being supported at the lower edge of said slot and comprising a portion fixed on said casing and a second portion, over which the release lever operates, movably supported on said casing, so that operation of the release lever will depress said second portion of the second strip bodily. 115

3. The combination with a typewriting 120 125 130

- machine, comprising a carriage and a de-
pressible release lever for said carriage, of
a sound-deadening casing for said ma-
chine; said casing comprising a body part
and a cover part, said body part and cover
part forming a slot at the front through
which said release lever projects, and means
for closing all of said slot not occupied by
the release lever, said means comprising op-
positely disposed strips, one of said strips
being supported on said cover part, the sec-
ond strip being supported on said body part
and comprising two portions, said release
lever operating over the right portion of
said second strip, said right portion being
movably supported on said body part to
swing about an axis parallel to said slot, so
that operation of the release lever will de-
press said right portion bodily, the left por-
tion of said second strip being fixedly
mounted on said body part.
4. The combination with a typewriting
machine, comprising a carriage and a de-
pressible release lever for said carriage, of
a sound-deadening casing for said machine,
said casing comprising a body part and a
cover part, said body part and cover part
forming a slot at the front through which
said release lever projects, and means for
closing all of said slot not occupied by the
release lever, said means comprising oppo-
sitely disposed strips, one of said strips be-
ing supported on said cover part, the second
strip being supported on said body part,
said release lever operating over a portion
of said second strip, that portion of said
second strip over which the release lever
operates being movably supported on said
body part, so that operation of the release
lever will depress said portion of the second
strip bodily, said movably supported por-
tion comprising a cushion and clamping
bars for said cushion forming a unit, one
of said bars having an upward extension
contacting with the release lever, so that op-
eration of the release lever will depress the
movably supported portion of the cushion
without crushing said cushion.
5. The combination with a typewriting
machine, comprising a carriage and a de-
pressible release lever for said carriage, of
a sound-deadening casing for said machine,
said casing comprising a body part and a
cover part, said body part and cover part
forming a slot at the front through which
said release lever projects, means for closing
all of said slot not occupied by the release
lever, said means comprising oppositely dis-
posed strips, one of said strips being sup-
ported on said cover part, the second strip
being supported on said body part and com-
prising two portions, one of said portions be-
ing fixed to the body part, the other of said
portions being movably supported on said
body part, said release lever operating over
- the movably supported portion to depress it
bodily when the release lever is operated,
a bracket fixed to said body part, said mov-
ably supported portion being pivotally
mounted on said bracket, means normally
pressing said movably supported portion
upwardly, and a stop on said bracket for
limiting the upward movement of said mov-
ably supported portion.
6. The combination with a typewriting
machine, comprising a carriage and a de-
pressible release lever for said carriage, of
a sound-deadening casing for said machine,
said casing comprising a body part and a
cover part, said body part and cover part
forming a slot at the front through which
said release lever projects, means for clos-
ing all of said slot not occupied by the re-
lease lever, said means comprising oppositely
disposed strips, one of said strips being
supported on said cover part, the second
strip being supported on said body part and
comprising two portions, one of said portions
being fixed to the body part, the other of
said portions being movably supported on
said body part, said release lever operating
over the movably supported portion to de-
press it bodily when the release lever is
operated, and forwardly-extending arms
fixed at their forward ends to said movably
supported portion, said arms being pivotally
mounted so that movement thereof raises or
lowers the movably supported portion.
7. The combination with a typewriting
machine, comprising a carriage and a de-
pressible release lever for said carriage, of
a sound-deadening casing for said machine,
said casing comprising a body part and a
cover part, said body part and cover part
forming a slot at the front through which
said release lever projects, means for closing
all of said slot not occupied by the release
lever, said means comprising oppositely dis-
posed strips, one of said strips being sup-
ported on said cover part, the second strip
being supported on said body part and com-
prising two portions, one of said portions
being fixed to the body part, the other of
said portions being movably supported on
said body part, said release lever operating
over the movably supported portion to de-
press it bodily when the release lever is op-
erated, a bracket fixed to said body part,
and forwardly-extending arms pivotally
mounted at one end on said bracket and fixed
to said movably supported portion at the
other end, so that movement of said arms
about their pivots raises or lowers the mov-
ably supported portion.
8. The combination with a typewriting
machine, including a ribbon-winding mech-
anism having a handle at one side of the
machine, of a sound-deadening casing for
said machine and enclosing said handle, said
casing having front, rear and side walls, one

- of said side walls having an opening permitting access to said handle, and means for closing said opening to prevent the escape of sound therethrough.
- 6 9. A sound-deadening casing for a typewriting machine having a forwardly-extending keyboard extension and a ribbon-winding mechanism including a handle at the side of the machine and enclosed by said casing, 70
10 the latter comprising a body portion having a front wall through which said keyboard extension projects, a back wall and side walls, the side wall adjacent said handle having an opening to give access to said handle, and a door for closing said opening.
- 15 10. The combination with a typewriting machine, including a ribbon-winding mechanism having a handle at one side of the machine, of a sound-deadening casing for 75
20 said machine and enclosing said handle, said casing having front, rear and side walls, one of said side walls having an opening permitting access to said handle, a pivotally mounted door for closing said opening to 80
25 prevent the escape of sound therethrough, and means for holding said door in closed position.
- 30 11. The combination with a typewriting machine, comprising a bell for giving a line-end bell signal, of a sound-deadening casing for 85
35 said machine, said bell being enclosed within said casing, and means for transmitting said bell signal to the outside of the casing, said means comprising a horn including collapsible sections, one of said sections 90
40 extending into the machine adjacent the bell, and another one of said sections projecting through the casing to the outside thereof.
- 45 12. The combination with a typewriting machine, comprising a bell for giving a line-end bell signal, of a sound-deadening casing for 95
50 said machine, said bell being enclosed within said casing, means for transmitting said bell signal to the outside of the casing, said means comprising a horn including collapsible sections, one of said sections 100
55 extending into the machine adjacent the bell, and another one of said sections projecting through the casing to the outside thereof, and means for deflecting the sound of said bell signal forwardly toward the front of the casing.
- 60 13. The combination with a typewriting machine, comprising a bell for giving a line-end bell signal, of a sound-deadening casing for 105
65 said machine, said bell being enclosed within said casing, means for transmitting said bell signal to the outside of the casing, said means comprising a horn including telescoping sections, one of said sections extending into the machine adjacent the bell, and another one of said sections projecting through the casing to the outside thereof, and a deflector tube mounted on the side 110
70 of the casing for deflecting the sound of the bell signal forwardly toward the front of the casing.
- 75 14. The combination with a typewriting machine, comprising a bell for giving a line-end bell signal, of a sound-deadening casing for 75
80 said machine, said bell being enclosed within said casing, means for transmitting said bell signal to the outside of the casing, said means comprising a horn including collapsible sections, one of said sections extending into the machine adjacent the bell, and another one of said sections projecting through the casing to the outside thereof, and a deflector tube mounted on the side 85
85 of the casing for deflecting the sound of the bell signal forwardly toward the front of the casing, said tube having its rear end in engagement with the outer end of the horn and its forward end terminating adjacent the front of the casing.
- 90 15. The combination with a typewriting machine, comprising a bell for giving a line-end bell signal, of a sound-deadening casing for 90
95 said machine, said bell being enclosed within said casing, and means for transmitting said bell signal to the outside of the casing, said means comprising a horn having one end extending into the body of the machine adjacent the bell, and the other end projecting through the casing to the outside thereof, the portion of the horn extending into the body of the machine being withdrawable to permit withdrawal of the machine from the casing.
- 100 16. The combination with a typewriting machine, comprising a bell for giving a line-end bell signal, of a sound-deadening casing for 100
105 said machine, said bell being enclosed within said casing, and means for transmitting said bell signal to the outside of the casing, said means comprising a horn having a fixed section and a movable section telescopically supported within said fixed section, said movable section extending into the body of the machine adjacent the bell, said fixed section projecting through the casing to the outside thereof, said movable section being withdrawable from the body of the machine and into the fixed section to permit withdrawal of the machine from the casing.
- 110 17. The combination with a typewriting machine, comprising a bell for giving a line-end bell signal, of a sound-deadening casing for 110
115 said machine, said bell being enclosed within said casing, means for transmitting said bell signal to the outside of the casing, said means comprising a horn having a fixed section and a movable section, telescopically supported within said fixed section, said movable section extending into the body of the machine adjacent the bell, said fixed section projecting through the casing to the outside thereof, said mov- 120
125
130

able section being withdrawable from the body of the machine and into the fixed section to permit withdrawal of the machine from the casing, and a finger-piece fixed to said movable section for moving the same into and out of said fixed section.

18. The combination with a typewriting machine, comprising a bell for giving a line-end bell signal, of a sound-deadening casing for said machine, said bell being enclosed within said casing, means for transmitting said bell signal to the outside of the casing, said means comprising a horn having a fixed section and a movable section, telescopically supported within said fixed section, said movable section extending into the body of the machine adjacent the bell, said fixed section projecting through the casing to the outside thereof, said movable section being withdrawable from the body of the machine and into the fixed section to permit withdrawal of the machine from the casing, and means fixed to the movable section and extending upwardly between the side of the machine and the casing for moving said movable section into and out of said fixed section.

19. The combination with a typewriting machine, comprising a bell for giving a line-end bell signal, of a sound-deadening casing for said machine, said bell being enclosed within said casing, means for transmitting said bell signal to the outside of the casing, said means comprising a horn having a fixed section and a movable section telescopically supported within said fixed section, said movable section extending into the body of the machine adjacent the bell, said fixed section projecting through the casing to the outside thereof, said movable section being withdrawable from the body of the machine and into the fixed section to permit withdrawal of the machine from the casing, an operating handle fixed to the movable section for moving it into and out of the fixed section, and means for guiding movable section in the fixed section.

20. The combination with a typewriting machine, comprising a bell for giving a line-end bell signal, of a sound-deadening casing for said machine, said bell being enclosed within said casing, and means for transmitting said bell signal to the outside of the casing, said means comprising a horn having telescoping sections, one of said sections projecting through the casing to the outside thereof, and another one of said sections extending into the machine and having the free end thereof terminating adjacent the bell, so that the latter provides a closure for said free end, whereby sounds produced within the machine other than those produced by the bell will not be transmitted to the outside of the casing.

21. The combination with a typewriting machine comprising a carriage, a ribbon-winding handle at one side of the machine, and a bell, at the other side of the machine, for giving a line-end signal, of a sound-deadening casing for said machine provided at one side with an opening to give access to said handle and at the other side with an opening adjacent said bell, said casing comprising a door to close the opening adjacent the handle, and a horn having its inner end adjacent said bell and its outer end projecting through the adjacent end of the casing, and fitting in the adjacent opening in the casing to co-operate with the bell in sealing the casing to prevent the passage of ordinary sounds of operation while transmitting the sound of the bell.

22. A slot-sealing means for a sound-deadening casing for a typewriting machine, comprising oppositely-disposed yieldable lips, one of which has a bodily shiftable section extending along the range of movement of a finger-piece on the carriage to be shifted by said finger-piece when the latter is actuated.

23. A slot-sealing means for a sound-deadening casing for a typewriting machine, comprising a locally-yieldable lip at one side of the slot and comprising a bodily shiftable section extending along the range of movement of a finger-piece on the carriage to be shifted by said finger-piece when the latter is actuated.

24. The combination with a typewriting machine, including ribbon-winding mechanism and a ribbon-winding handle at one side of the machine, of a sound-deadening casing for said machine and enclosing said handle, said casing including front, rear and side walls, one of said side walls having an opening adjacent the handle permitting access to the latter, a door swingably mounted upon the outer side of said casing for sealing said opening, and a detent engaging said door for holding the same closed against said opening.

25. The combination with a typewriting machine, including ribbon-winding mechanism and a ribbon-winding handle at one side of the machine, of a sound-deadening casing for said machine and enclosing said handle, said casing including front, rear and side walls, one of said side walls having an opening adjacent the handle permitting access to the same, a door swingably mounted upon the outer side of said casing for sealing said opening, a finger-piece fixed to said door, and a spring device co-operating with the free end of said door for holding the same closed against said opening.

26. The combination with a typewriting machine, including a bell for giving a line-end signal, of a sound-deadening casing for the machine having an opening in a side

wall thereof and into which the bell is received, the latter providing a closure for said opening, whereby sounds produced within the casing other than those caused by the bell will not be transmitted to the outside of the casing, and a deflector tube fixed to the outer face of said side wall and

communicating with said opening for conveying the sound of the bell to the operator of the machine.

BURNHAM C. STICKNEY.
